(57) **CLAIM**

The ornamental design for a portion of an electronic camera, as shown and described.

DESCRIPTION

FIG. 1 is a front perspective view of a portion of an electronic camera showing our new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a rear view thereof.

The broken line showing of a remainder of the electronic camera in the figures, including the unshaded areas therein, is for illustrative purposes and forms no part of the claimed design.
